UNITED STATES PATENT OFFICE.

CARL FEDDERN, OF PHILADELPHIA, PENNSYLVANIA, ASSIGNEE TO GLOBE TICKET COMPANY, OF PHILADELPHIA, PENNSYLVANIA, A CORPORATION OF PENNSYLVANIA.

CHECK HOLDER.

Application filed July 30, 1920. Serial No. 400,113.

To all whom it may concern:

Be it known that I, CARL FEDDERN, a citizen of the United States, residing at Philadelphia, in the county of Philadelphia and State of Pennsylvania, have invented new and useful Improvements in Check Holders, of which the following is a specification.

My present invention relates to improvements in holders for tickets or sales checks, and more especially to those of the kind adapted for use in restaurants for indicating the amounts of the purchases. The primary object of the invention is to provide a novel and improved holder for securing a pack of tickets or checks to a support, whereby the pack will be held securely until all the tickets or checks in the pack have been used or removed, whereupon the remaining stub can be easily and quickly removed and replaced by another pack of tickets or checks, this operation requiring but slight effort on the part of the operator and rendering it unnecessary to employ keys, or other adjuncts for this performance.

To this end the invention consists in certain improvements and combinations and arrangements of parts, all as will be herein-after more fully described, the features of novelty being pointed out particularly in the claims at the end of the specification.

In the accompanying drawing:

Figure 1 is a perspective view of a ticket or check holder constructed in accordance with the preferred embodiment of the invention;

Figure 2 is a front or face view of the device, showing the pack holder in unfastened condition;

Figure 3 represents a section taken centrally and longitudinally of the device; and

Figure 4 represents a transverse section through the device on the line 4-4 of Figure 3.

Similar parts are designated by the same reference characters in the several views.

The present invention is applicable generally to devices of various kinds, wherein it is desirable or necessary to secure or hold a pack of tickets or checks upon a suitable support. The invention is applicable more

especially to ticket or sales check holders of the kind commonly employed in restaurants and which are carried by the waiters and adapted to be issued to the patrons to indicate the amounts of the purchases or the amount to be paid to the cashier. The preferred embodiment of the invention is shown in the accompanying drawing and will be hereinafter described in detail, but it is to be understood that the invention is not restricted to the precise construction shown, as equivalent constructions are contemplated and these will be included within the scope of the claims.

In the present instance, the device comprises a base or a member 1 which may, as usual, be provided with a loop or clasp, whereby it may be attached to a belt or other fastening worn by the waiter. The pack of tickets or checks, designated X, is adapted to be applied to the face of this plate or member and preferably the upper end of said plate is bent forwardly at substantially a right angle, as at 2. The pack of tickets or checks employed is preferably of the kind which comprises a stub portion at one end, while the remainder is to be detached, for which purpose the stub portions of the tickets or checks may be provided with scorings or weakened lines to facilitate detachment of the bodies of the tickets or checks.

The pack of tickets or checks is secured to the plate or member 1 by a holder, which, according to the present invention, comprises a gripping member 3 and a cooperative locking member 4. The gripping member 3 is composed preferably of flat spring steel, or other suitable material, which is bent into substantially the form of a yoke, the intermediate portions of this gripping member resting against the forwardly bent portion 2 of the plate, while the two arms 5 and 6 of the gripping member straddle the upper or stub end of the pack, and the terminals 7 and 8 of these arms are preferably bent inwardly to provide jaws, the edges of which are adapted to engage and grip the opposite edges of the pack. In the particular embodiment of the invention shown, the

opposite edges of the pack, at points substantially in line with the dividing lines between the stub portions and the body portions of the tickets or checks, are provided with substantially V-shaped notches, into which the inturned ends 7 and 8 of the arms 5 and 6 of the gripping member may enter, although in some instances the holder may be employed in connection with packs of tickets or checks which are without such notches. The normal resilience of the gripping member acts to relatively separate the arms 5 and 6, as shown substantially in Figure 2, and while the arms of the gripping member are in such condition, the stub of the used pack may be easily removed from its position between these arms, and another pack of tickets or checks may be easily inserted. The member 4 serves to force the jaws 7 and 8 of the gripping member into gripping and securing relation with the opposite edges of the pack. Preferably and as shown, this locking member is in the form of a clip having sides 9 and 10, an end 11 and a top 12. The locking member is also preferably pivoted to the plate or member 1, on the pivot pin 13, as shown in the present instance, which extends through the sides 9 and 10 of the locking member and through lugs or flanges 14, which extend downwardly from the part 2 of the plate 1. In the present instance, the pivot pin 13 also extends through the arms 5 and 6 of the gripping member and thus serves to retain the gripping member in operative relation with the back plate 1. When the locking member 4 is swung downwardly or into the position shown in Figures 1 and 3 (full lines), the sides 9 and 10 of the locking member come into engagement with the divergent arms 5 and 6 of the gripping member and thereby force these arms inwardly, causing the jaws 7 and 8 on the terminals of the gripping member to press inwardly against the opposite edges of the pack, with the result that the pack is held immovably and securely on the plate or member 1. The sides 9 and 10 of the locking member are preferably bent inwardly at their corners, as at 15 and 16, so that when the locking member has been moved into fully locked position, these inwardly bent corners will bear on the sides of the arms 5 and 6 of the gripping member, adjacent to the plate or member 1, and will thus frictionally hold the locking member in locked position, although the locking member may be readily swung into unlocked position, when the stub of a used pack is to be removed and another pack substituted. A ticket or check holder embodying the present invention is capable of firmly and immovably securing a pack of tickets or checks or a portion of such a pack to a base plate or other suitable support, and the security with which the pack is held is not im-

paired by the detaching of the tickets or checks from the stub. When the supply of tickets or checks in the pack has become exhausted, the stub remaining may be easily and quickly removed and replaced by another pack, without requiring the use of a key or other tool, it being necessary merely to swing up the locking member with a force sufficient to overcome the friction which normally holds it in locking position, such movement of the locking member causing the gripping member, by its inherent resiliency, to release its grip upon the stub of the pack. The invention also avoids the necessity of employing loose parts which would be likely to become lost or misplaced. I claim as my invention—

1. The combination of a support adapted to receive a pack of checks and having a forwardly bent portion at one end, a yoke-shaped gripping member composed of a strip of flat resilient material formed separately from the support but having its intermediate portion abutting flatwise against said forwardly bent portion of the support, said yoke-shaped member forming opposed arms extending longitudinally of the support, said arms being arranged to engage opposite sides of a pack on said support and having a normal tendency to spread apart, and a locking member cooperative with the arms of the gripping member to force them into gripping engagement with the pack. 90

2. The combination of a support adapted to receive a pack of checks and having a forwardly bent flat portion at one end thereof, a gripping member composed of a strip of flat resilient material bent into the shape of a yoke and having an intermediate portion which abuts flatwise against said forwardly bent portion of the support, said gripping member having opposed arms adapted to occupy positions extending longitudinally at opposite sides of a pack on said support, and a locking member having sides to move into engagement with the outer sides of the arms on the gripping member and thus force said arms inwardly into gripping engagement with an interposed portion of the pack, the sides of the locking member also having inwardly bent corners to cooperate with the arms of the gripping member when the locking member is in locking position. 115

3. A check holder comprising in combination a support adapted to receive a pack of checks and having a forwardly bent flat portion at one end, a yoke-shaped gripping member composed of a strip of flat resilient material formed separately from the support but having its intermediate portion presented flatwise to said forwardly bent portion of the support, said yoke-shaped member forming opposed arms which ex- 125

tend longitudinally of the support and are arranged to engage opposite sides of a pack thereon, a locking member having sides arranged to cooperate with the outer sides 5 of the opposed arms of the gripping member to force said arms into gripping relation with a pack on the support, and a pivot mounted on said support and extending through the sides of the locking member 10 and the opposed arms of the gripping mem-

ber to retain the gripping member on the support and to pivotally mount the locking member on the support.

In testimony whereof I have hereunto set my hand in presence of two subscribing witnesses. 15
